UNITED STATES PATENT OFFICE.

CHARLES FREDERICK LAGANKE, OF CLEVELAND, OHIO, AND JOHN A. SMITH, OF ATHENS, TENNESSEE, ASSIGNORS TO THE FISHER BOOK TYPEWRITER COMPANY, OF CLEVELAND, OHIO, A CORPORATION OF DELAWARE.

RIBBON GUIDING, GUARDING, AND SHIFTING MECHANISM FOR TYPE-WRITING MACHINES.

SPECIFICATION forming part of Letters Patent No. 723,884, dated March 31, 1903

Application filed June 21, 1901. Serial No. 65,496. (No model.)

To all whom it may concern:

Be it known that we, CHARLES FREDERICK LAGANKE, residing at Cleveland, in the county of Cuyahoga and State of Ohio, and JOHN A. SMITH, residing at Athens, in the county of McMinn and State of Tennessee, citizens of the United States, have invented a new and useful Ribbon Guiding, Guarding, and Shifting Mechanism for Type-Writing Machines, 10 of which the following is a specification.

This invention relates to improvements in type-writing machines, but more particularly to ribbon guiding, guarding, and shifting mechanism therefor.

15 The object of the invention is to provide a simple, durable, inexpensive, and efficient construction of ribbon supporting and guiding mechanism for guiding and protecting the ribbon passing between the ribbon-spools 20 in close contiguity to the platen, said mechanism being organized and arranged in a manner to permit the ribbon to be shifted laterally to present different tracks or stripes thereof at the printing-point, so that as the 25 ribbon is fed longitudinally the type will strike along a ribbon stripe or track constituting one of a number which may be utilized by reason of the lateral shifting of the ribbon.

30 A further object of the invention is to facilitate the use of the machine for printing in different colors by equipping said machine with a ribbon having stripes, bands, or tracks of the several colors desired or with a plurality of different-colored ribbons, either of 35 which stripes or ribbons may be presented over the printing-point by the shifting of the ribbon-spools and guiding-frame.

A further object of the invention is to provide means for moving the ribbon laterally to displace it from the printing-point a sufficient distance to expose the printing and to provide the machine with an automatically-operated line finder or indicator arranged to 40 be moved to the printing-point to facilitate the positioning of the printing mechanism whenever the ribbon is moved out of its normal plane, the displacement of the ribbon and the movement of the line-finder to its in-

dicating position being simultaneously effected by means of a single ribbon-shift key.

A still further object of the invention is to equip the type-writing machine with a ribbon-indicator exposed adjacent to the keyboard to indicate which stripe or longitudinal track of the ribbon is presented at the printing-point and to enable the operator to readily shift either of the other stripes or tracks of the ribbon to the printing-point, accordingly as it is desired to print in different colors or to employ an unused portion of the same-colored stripe for the succeeding printing operation.

Further and subordinate objects of the invention will appear more fully hereinafter as the necessity for their accomplishment is developed in the succeeding description of that form of the invention which for the purpose of this disclosure we have illustrated in the accompanying drawings.

In said drawings, Figure 1 is a front elevation of a Fisher type-writing machine equipped with the subject-matter of our present invention. Fig. 2 is a rear elevation of the subject-matter of Fig. 1. Fig. 3 is an end elevation, partly in section, of the type-writing machine, showing the ribbon-shift key depressed in dotted lines and the depressed position of the ribbon and the indicating position of the line-finder likewise being shown in dotted lines. Fig. 4 is a view similar to Fig. 3, but looking toward the opposite end of the machine. Fig. 5 is a horizontal sectional view on the line 5 5 of Fig. 1, showing the ribbon supporting and guiding mechanism and the line-finder in plan. Fig. 6 is a longitudinal sectional view of a portion of the type-writing machine and the ribbon mechanism. Fig. 7 is a detail perspective view of one of the ribbon-guards detached. Fig. 8 is a detail sectional view on the line 8 8 of Fig. 6. Fig. 9 is a detail perspective view of the ribbon-displacing and line-finder operating key and its connections and also the ribbon-indicator and the lateral ribbon-shift lever and stop. Fig. 10 is a detail perspective view of the mechanism for operating the line-finder and printing-point indicator. Fig. 11 is a de-

- tail perspective view of one of the ribbon-spools and the adjacent end of the ribbon-guiding frame and a portion of one of the ribbon-guards. Fig. 12 is a detail sectional view of one of the ribbon-spools, illustrating the construction and mounting thereof and the manner of attaching the ribbon-guiding frame thereto. Fig. 13 is a sectional elevation illustrating the mechanism employed to feed a ribbon supported and guided in accordance with our invention. Fig. 14 is a detail sectional view illustrating one feature of the mechanism shown in Fig. 13, and Fig. 15 is a detail perspective view of one of the pawls which serve to connect the spool-shafts with their operating mechanism.
- Like characters of reference are employed to designate corresponding parts throughout the views.
- The ribbon supporting, guiding, and guarding mechanism and the mechanism employed for shifting the ribbon laterally either to displace it entirely from its normal position or to present the various longitudinal stripes or tracks thereof to the types are susceptible of use in connection with various kinds of type-writing machines; but for the purpose of the present disclosure we have illustrated the invention in connection with a machine of that type now in extensive use and known commercially as the "Fisher" type-writing machine. The subject-matter of this invention is designed with special reference to the equipment of the Fisher machine, which has come to be largely employed in commercial billing, one of the requisites of which is the use of the usual debit and credit colors, black and red, for the entry of the debit and credit items.
- In order to make the disclosure as comprehensive as possible by showing a complete ribbon-operating mechanism, we have illustrated in connection with the subject-matter of our invention the ribbon-feeding and feed-shifting mechanism invented by John A. Smith and described and claimed in his concurrent application, Serial No. 65,475.
- The machine illustrated in the drawings involves in its general organization a carriage-supporting frame 1, disposed to travel upon the main tracks or guides 2 and provided with front and rear carriage-guides 3 and 4, supporting the printing mechanism or carriage 5, which is mounted to travel in the direction of letter-spacing and is provided with a pendent type-bar-supporting ring 5^a. The frame 1, variously called the "traveling-machine" frame or the "carriage-supporting" frame, is equipped with ordinary line-spacing mechanism which is employed in the manner well understood in the art to advance the frame 1 in line-for-line progression over the flat platen, which characterizes machines of the type illustrated. The carriage 5 is arranged to be drawn to the right, or in the direction of letter-spacing, by suitable means (not illustrated) and is equipped, as shown, with

escapement mechanism for effecting the step-by-step advance of the carriage in the manner set forth in the patent to R. J. Fisher, No. 573,868. This mechanism constitutes no part of the invention and is therefore omitted from the drawings. With this carriage-feeding mechanism for regulating the step-by-step feed of the carriage in the direction of letter-spacing is combined a carriage-release mechanism, including a primary element or release-lever 7, mounted within the carriage-easing, as shown in Fig. 4 of the drawings, and having operative connection with a release-key 8, by the depression of which the carriage may be released to permit its free movement upon the guides of the machine-frame. The release-lever 7 and its key are described in the Fisher patent aforesaid and are only shown because said lever constitutes the operating member of ribbon-release mechanism illustrated in the drawings for the purpose of completing the disclosure of an entirely operative construction, but constituting a feature described and claimed in the aforesaid concurrent application of John A. Smith. From the bottom of the carriage, at the opposite ends thereof, depend suitable spool-shaft hangers 9, rotatably supporting a pair of parallel spool-shafts 10 and 11, located slightly beyond the opposite ends of the carriage and serving to support the ribbon-spools 12 and 13. The ribbon-spools are designed to rotate with the spool-shafts for the purpose of causing the feed of the inking-ribbon 14 in one direction or the other, as the carriage is advanced in the direction of letter-spacing during the printing operation.

Before proceeding with a detail description of that portion of the construction with which our present invention is directly concerned it may be well, in order that a comprehensive understanding of the operation of the printing mechanism may be had, to refer briefly to the illustrated construction of ribbon-feeding and feed-shifting mechanism invented by John A. Smith, as heretofore stated. As shown more particularly in Fig. 13, said mechanism comprehends spool-pinions 15 and 16, loosely mounted on the spool-shafts 10 and 11, and arranged for connection with said shafts to rotate them by means of ratchet-wheels 17 and 18, fixed upon the shafts for engagement with spring-pressed pawls 19 and 20, carried by and movable with the pinions. Intermediate of the pinions is disposed a shift-bar 21, carrying shift-pinions 22 and 23, constantly meshing with an operating-rack 24, mounted upon the machine-frame independently of the carriage. The shift-bar is designed to be moved for the purpose of bringing either of the shift-pinions into mesh with a spool-pinion to effect the rotation of either of the pinions, as it is desired to cause the feed of the ribbon in one direction or the other when the machine is moved in the direction of letter-spacing. For the purpose of entirely releas-

ing the ribbon-operating mechanism to stop the feed ribbon-release mechanism is employed. This mechanism includes a pair of beveled disks 25 and 26, shiftably mounted 5 on the spool-shafts and arranged to be urged toward the pinions for the purpose of lifting the pawls 19 and 20 out of engagement with the ratchet-wheels, and thereby totally disconnecting the spool-pinions from the shafts. 10 The disks are urged or shifted by means of a rock-shaft 27, having suitable connection with said pinions, as shown, and provided with an upstanding arm 28, operatively related to the release-lever 7. (See Figs. 4 and 15 13.) Both ends of the ribbon 14 are wound upon the ribbon-spoils 12 and 13 in the same direction in order that the positive longitudinal feed of the ribbon may be effected in one direction or the other, accordingly as one pinion 20 or the other is geared to the operating-rack. Thus we see that the ribbon may be fed longitudinally in either direction, as desired, or may be entirely released to stop the feeding thereof whenever the carriage is released from 25 its escapement mechanism and is free to be shifted back and forth upon the machine-frame. It is of course understood that this longitudinal feed of the ribbon is designed to prevent the type from striking continuously 30 thereon at the same point, and therefore as the ribbon is advanced a narrow stripe or track thereof will be presented directly above the printing-point. It will therefore be evident that in order to present different portions or stripes of the ribbon at the printing-point, either for the purpose of utilizing the entire area of the ribbon or for presenting stripes of different colors to the type, the ribbon must be shifted laterally, and the present 35 invention therefore comprehends novel means for supporting and guiding the ribbon and for shifting the same laterally, either to displace the ribbon entirely from the printing-point or to present thereto the different-colored portions of the ribbon in order to facilitate the use of the machine for printing in different colors—as, for instance, in entering debit and credit items in commercial billing. 40 That portion of each of the spool-shafts disposed between the hangers is of angular cross-sectional contour, and the angular portion of each shaft slidably supports the bearing-thimbles 29 and 30, the internal contours of which correspond to the external contour of 45 the shaft. These bearing-thimbles are secured within the opposite ends of the hollow hub 31 of the ribbon-spool, and their opposite ends project slightly beyond the heads 32 of the spool in order to provide trunnions 50 or journals for reception within annular bearing-rings 33, formed at the upper ends of the arms 34 of the ribbon-frame-supporting brackets 35. By reason of this mounting the spools are rotated with the spool-shafts, but 55 are free to be shifted longitudinally thereon for the purpose of displacing the ribbon from the printing-point or for presenting any one

of the several stripes or tracks of the ribbon to the types. The bearing trunnions or studs of the spools rotate freely within the bearing-rings 33 of the ribbon-frame-supporting brackets 35, and said brackets are secured in any suitable manner to the vertically-disposed end portions 36 of the ribbon supporting and guiding frame 37. The ribbon-guiding frame is designed to lead the ribbon under the type-ring and extends from one spool to the other, and it preferably comprises a pair of right-angular sheet or plate metal end members 38, having downwardly and outwardly disposed side flanges 39 and a more or less open intermediate member or ribbon-plate 40. (See Figs. 5 and 6.) The plate 40 is secured at its opposite ends, as by rivets or the like, to the contiguous extremities of 85 the end members 38 and is cut out to form forwardly-extending parallel ribbon-guides 41 and 42 and guiding-fingers 43 and 44. The ribbon-guides 41 and 42 are disposed adjacent to but at opposite sides of the printing-point, 90 and their contiguous side edges are turned down to form ribbon-depressing flanges 45, which insure the location of the ribbon in close proximity to the writing-surface at the printing-point. The ribbon 14, passing between the spools, extends around or under the ribbon-guiding frame and is threaded over the guiding-fingers 43 and 44 and under the guides 41 and 42, the opposite edges of the ribbon being protected by the side flanges 100 39 of the end members 38 of the ribbon-frame. Inasmuch as the arms of the frame-supporting brackets 35 are opposed to the opposite ends of the spools it will be seen that the spools and frame must of necessity move 105 in unison when the latter is shifted laterally, and in order to insure the proper longitudinal disposition of the guide-frame during the shifting thereof the horizontal portions of its end members are provided with upstanding 110 guide-studs 45^a, movable within guide-loops 46, secured to the type-ring 5^a, adjacent to the opposite ends of the frame.

For the purpose of making the special utility of the present invention perfectly apparent 115 we have illustrated a black ribbon provided along its rear longitudinal edge with a narrow stripe, band, or track of red, (indicated by the letter a.) This stripe or band is of a width little more than that required for the impact 120 of a single type; but the black portion b of the ribbon is of such width as to comprehend a number of such tracks—that is to say, the black band or stripe b is of such width that each edge thereof and the middle portion, respectively, may be used as separate tracks, each being used as the ribbon is fed longitudinally and displaced by another when the ribbon-guiding frame is shifted laterally the desired distance, in a manner to be hereinafter more fully described. 125

The mechanism for shifting the ribbon frame and spools laterally preferably includes a ribbon-shift key 47, formed at one end of

the ribbon-shift lever 48, secured to the inner end of a rock-shaft 49, having its extremity forked, as indicated at 50, for engagement with a stud 51, projecting from one of the 5 frame-supporting brackets 35. The rock-shaft 49 is supported in suitable bearings 52, pendent from the carriage, and at its end opposite the lever 48 the shaft is provided with an arm 53, the forked end of which engages 10 a stud 54, extending from the supporting-bracket 35 at the adjacent end of the ribbon-frame. Except when prevented by means to be described the ribbon-frame is designed to occupy an extreme forward position, which 15 will present the narrow red stripe *a* above the printing-point, and said frame is therefore urged forwardly by suitable reactive means—as, for instance, a spring 55, coiled upon the rock-shaft 49 and having its opposite ends 20 engaged by a set-collar 56, secured to the shaft, and a post 57, secured to the bottom of the carriage-casing. (See Fig. 6.) The upper end of the ribbon-shift lever 48 is laterally offset and is guided in its movement by a laterally-disposed slotted guide-flange 58, formed along the front inclined edge of a bracket-plate 59, screwed or otherwise secured to one end of the carriage-casing, as best shown in 25 Figs. 3 and 9. By reference to Fig. 3 it will be noted that the ribbon-shift key 47 when depressed to the lower end of the guide-flange 58 will cause the ribbon and its frame to be laterally shifted a sufficient distance to entirely displace the ribbon from the printing-point, and as the front of the carriage is open 30 (see Fig. 1) this shifting of the ribbon will reveal the writing for the inspection of the operator, and upon the release of the key 47 the spring 55 will automatically return the 35 ribbon to its initial position. If, however, the return of the ribbon-shift lever 48 is prevented, it is evident that the complete return of the ribbon to its initial position will likewise be prevented, and as the narrow 40 red stripe will not reach the printing-point it is evident that the black stripe *b* of the ribbon will be presented to the printing-point instead. In other words, the precise portion 45 of the ribbon which will be presented to the printing-point is determinable by the extent of the return movement of the shift-lever 48, and by providing suitable adjustable stop mechanism for arresting the return movement of the lever at different points any one 50 of the several stripes or tracks of the ribbon 55 may be presented to the types without interfering with the proper operation of the ribbon feeding, shifting, or releasing mechanism. A convenient device for accomplishing this 60 result comprehends the employment of a swinging plate 60, pivoted upon the bracket-plate 59 and having a laterally-disposed stop 61 located in rear of the lever 48 and capable of being adjusted to arrest the return 65 movement of the lever at the several points corresponding to the impression tracks or stripes of the ribbon. The plate 60 is moved

to its several positions and is retained by means of an upstanding spring-arm 62, passing upwardly through a slot 63 in what we 70 shall term the "ribbon-indicator flange" 64, extending laterally from the upper edge of the plate 59. The outer side wall of the slot 63 is formed with a series of stop-shoulders 65, which, together with the rear end of the slot, 75 constitute means for retaining the arm 62 in its several predetermined positions, it being observed that the resiliency of the arm will cause it to spring into engagement with the successive stop-shoulders as the lever is 80 moved forward by the operator. Thus when the arm 62 is located at the rear end of the slot 63, as indicated in Fig. 9 of the drawings, the stop 61 will be in a position to permit the complete retraction of the lever 48 and a 85 complete return of the ribbon to its extreme forward position, thus presenting the rear-most stripe or impression-track of said ribbon at the printing-point. If now the arm 62 is advanced to the next stop-shoulder, the stop 90 61 upon the plate 60 will urge the lever 48 forward and will cause the ribbon to be shifted laterally to a sufficient extent to displace the rearmost track or stripe from the printing-point and to replace it by the next 95 laterally-adjacent track, which in the illustrated form or ribbon will be the rear edge of the black band *b*, or if after using the black ribbon it is desired to make a credit entry in red ink the arm 62 may be pressed 100 laterally to disengage it from its shoulder, and upon such release being effected the force exerted by the spring 55 will rock the shaft 49 and swing the lever 48 sufficiently to move the ribbon-frame and the ribbon to 105 their extreme forward positions.

It is very desirable to provide simple means located at the keyboard for indicating to the operator the precise position of the ribbon, and particularly is this true where a ribbon 110 bearing stripes of different colors is employed, because obviously it will be desirable to know what color is presented to the printing-point and in what direction the ribbon-shifting mechanism should be moved in order to present the desired color in position for presentation to the type. We therefore provide what may be termed a "ribbon-indicator" 115 for indicating the particular portion of the ribbon presented at the printing-point in any 120 given position of the arm 62. The preferable form of such indicator is shown in Fig. 9 of the drawings and comprises a series of side openings 66, disposed opposite the several stop-shoulders 65 and within which are 125 exposed the various colors which will be presented at the printing-point, according to the position of the arm 62. Thus the ribbon shown (see Fig. 5) is of a sufficient width to embody four laterally-opposed longitudinal 130 impression tracks or stripes, the rear one of which is red. Therefore the indicator plate or flange 64 is provided with four stop-shoulders 65, one for each of the several impres-

sion tracks or stripes, and opposite these shoulders are exposed a red disk 67 and three black disks 68, said disks corresponding in number and color to the several impression stripes or tracks of the ribbon. It is evident, however, that these indications of the positions of the ribbon and the color of its stripes may be varied—that is to say, instead of employing color-symbols, as shown, the flange 64 might be provided with a scale having significant indications of any desired character—as, for instance, the words "Red," "Black," &c. Instead, however, of effecting the lateral movement of the ribbon by the manipulation of the arm 62 the operator may, if he so desires, depress the ribbon-shift key 47, then adjust the arm 62 to present the stop 61 at the proper point, and permit the shift-lever 48 to swing back against the stop. As heretofore stated, it is contemplated to shift the ribbon laterally not only to present either of its impression-tracks to the printing-point, but also to entirely remove the ribbon from the printing-point in order to reveal the work, and in a further development the present invention comprehends the employment of a line finder and indicator, which while normally retained at a point removed from the ribbon will be automatically moved to the printing-point, so that the operator may readily position the machine at the proper point to continue the printing after the machine has for any reason been removed therefrom. For example, if the machine has been moved back over the platen away from the printing for the purpose of permitting an erasure to be made the operator by depressing the ribbon-shift key 47 may remove the ribbon and its frame from their normal positions over the printing-point and at the same time automatically present the line-finder at the printing-point of the machine—that is to say, that point at which the types are presented when the letter-keys are depressed. With the line-finder in position the machine is moved back over the platen until the finder indicates both the line and the point at which the next type impression is to be made. The key 47 is then released, the line-finder returns to its inactive or normal position, and the ribbon-shift lever 48 is arrested to present the proper impression-stripe of the ribbon to the type in accordance with the predetermined position of the stop 61. It will be noted that the stop 61 is adjustable to different positions to arrest the return movement of the ribbon-supporting means at different points and that said stop having once been adjusted to present a given stripe of the ribbon normally at the printing-point the ribbon may be shifted any number of times to expose the writing to view without interfering with the adjustment of the stop. Thus having once adjusted the stop the operator is at liberty to shift the ribbon as often as may be desirable during the course of the work, and upon its return the proper stripe

of the ribbon will always be presented in position at the printing-point.

A simple embodiment of line-finder and operating mechanism therefor is disclosed in the drawings. The line finder proper is embodied in the form of a small swinging plate or indicator 69, secured at one end to a rock-shaft 70 and located in a central depression 71, formed in a transverse frame-bar 72, extending between the front ends of the crescent-shaped type-ring 5^a. The opposite side portions of this depression 71 constitute bearings for the rock-shaft 70, which latter is extended through a depending bearing-flange 73, formed at one end of the bar 72, and is provided just beyond said flange with a cam-arm 74. (See Fig. 10.) The line finder and indicator 69 is designed normally to occupy a more or less elevated position, as shown in Fig. 10, so as to prevent it from interfering with the ribbon and to remove it out of the path of the type-heads located at the outer ends of the type-arms, and in order to insure the retention of the line-finder in its normal position the shaft 70 is provided with a return-spring 75, encircling the shaft and secured at its opposite ends to said shaft and to the bar 72.

The depression of the line-finder 69 is effected by means of a sliding bar or plunger 76, having a curved nose 77 at its lower end bearing upon the cam-arm 74. The slide-bar 76 is provided with longitudinal slots 78 for the reception of headed screws 79, screwed into the side face of one of the front hanger-rods 80 for the type-ring. Adjacent to the upper end of the bar 76 it is provided with a laterally-disposed pin 81, disposed in the path of an arm 82, extending laterally from the rock-shaft 49. The arm 82 is not connected to the pin 81, but is spaced therefrom by a suitable interval to produce considerable lost motion of the rock-shaft with respect to the actuation of the line-finder—that is to say, the arm 82 does not contact with the pin 81 to operate the line-finder until the ribbon-shift lever 48 has nearly reached the limit of its forward movement, and therefore when the ribbon is shifted laterally for the purpose of presenting the different impression-stripes thereof to the printing-point the line-finder is not operated; but when the ribbon is moved sufficiently to entirely displace it from the printing-point the latter part of said movement will be accompanied by a simultaneous movement of the line-finder, so that the latter will be presented to the printing-point when the ribbon has been entirely displaced. Thus assuming the parts to be in the positions shown in Figs. 9 and 10 the key 47 may be actuated to present either of the four impression-stripes of the ribbon to the printing-point; but if it is further depressed after the fourth stripe is in the printing position the arm 82 will have contacted with the pin 81, forcing the bar 76 downward and causing said bar by reason of its operative en-

gagement with the cam-arm 74 to rock the shaft 70, and thereby depress the line-finder to the position shown in dotted lines in Fig. 3.

For the purpose of preventing the ribbon 5 or that portion thereof which passes under the ribbon-frame from coming in contact with the work-sheet, except at the printing-point, it is intended to employ a pair of ribbon-guards 83 and 84, detachably secured to the 10 end members of the frame. These guards are in the form (see Fig. 7) of plates or strips having their outer ends bent up, as indicated at 83, and provided along their opposite sides with holding flanges or guides 86, bent inwardly, as shown in the drawings, to slidably engage the side flanges 39 of the horizontal portions of the end members 38, said last-named flanges being bent outwardly or in divergent relation, as shown in Fig. 8. By reason 15 of these interfitting flanges the guards may be readily slid upon the end members of the frame, so as to dispose their horizontal portions below the ribbon, (see Fig. 6,) and in order to prevent the accidental detachment of the guards their upturned ends are provided with spring engaging arms 87, which grip the opposite sides of the vertical portions 36 of the ribbon-frame when the guards have been slid to place.

It is thought that from the foregoing the construction, operation, and special utility of our invention will be apparent; but while the present embodiment of said invention is thought at this time to be preferable we reserve the right to effect such changes, modifications, and variations of the illustrated structure as may be suggested by experience or experiment and embraced within the scope of the protection prayed.

40 What we claim is—

1. In a type-writing machine, the combination with the frame and carriage, of ribbon-supporting means, a ribbon-shift key located at or adjacent to the keyboard and arranged 45 to shift the ribbon laterally, and an adjustable stop mounted independently of the key and disposed to limit the return movement thereof.

2. In a type-writing machine, the combination with the frame and carriage, of ribbon-supporting means, a ribbon-shift lever for shifting the ribbon laterally, an adjustable stop for limiting the movement of the shift-lever in one direction, and an indicator disposed adjacent to the stop for indicating the 55 position of the ribbon.

3. In a type-writing machine, the combination with the frame and carriage, of ribbon-supporting mechanism, a ribbon-shift lever 60 connected thereto and designed to shift the ribbon laterally, an adjustable stop mounted independently of the lever and disposed in the path of movement thereof, and an indicator having significant designations corresponding to the impression tracks or stripes of 65 the ribbon.

4. In a type-writing machine, the combination with the frame and carriage, of ribbon-supporting means, a shift-lever arranged to move said ribbon laterally for the purpose of 70 removing the ribbon from the printing-point, and adjustable means for limiting the return movement of the lever, whereby any desired impression track or stripe of the ribbon will be presented at the printing-point. 75

5. In a type-writing machine, the combination with the frame and carriage, of ribbon-supporting means, a ribbon-shift lever mounted on the carriage and arranged to move the ribbon-supporting means laterally, 80 a swinging stop disposed in the path of the lever, and means for adjusting the stop to different positions corresponding to the impression tracks or stripes of the ribbon.

6. In a type-writing machine, the combination with the frame and carriage, of ribbon-supporting means, a ribbon-shift lever disposed to shift the ribbon laterally, a bracket-plate provided with guiding means for the lever, an adjustable stop carried by said 90 bracket-plate to limit the movement of the shift-lever, an arm for operating said stop, and a ribbon-indicator disposed contiguous to said arm.

7. In a type-writing machine, the combination with the frame and carriage, of ribbon-supporting means, a ribbon-shift key supported by the carriage and disposed to shift the ribbon laterally, and an adjustable stop device mounted on the carriage independently of the shift-key and disposed to limit the movement thereof in one direction. 95

8. In a type-writing machine, the combination with a frame and carriage, of ribbon-supporting mechanism, a shift-key mounted on 105 the carriage and connected to the ribbon-supporting mechanism to shift the ribbon laterally, a bracket-plate secured to the carriage and having guiding means for the shift-key, a swinging arm mounted on said plate independently of the key and provided with a stop for limiting the movement of the key in one direction, and a flange extending from the plate and provided with spaced retaining devices for the swinging arm, and with a ribbon-indicator the characters of which are located opposite the several retaining devices for the arms. 110

9. In a type-writing machine, the combination with the frame and carriage, of ribbon-supporting means, a reactive device for moving the ribbon laterally in one direction, a shift-key for moving the ribbon laterally in the opposite direction in opposition to said reactive device, and adjustable means for limiting the return movement of the shift-key. 115

10. In a type-writing machine, the combination with the frame and carriage, of ribbon-supporting means, a reactive device for urging the ribbon laterally in one direction, a shift-key for urging the ribbon laterally in the opposite direction in opposition to said 120

reactive device, and an adjustable stop mounted independently of the shift-key and disposed to limit the return movement thereof.

11. In a type-writing machine, the combination with the frame and carriage, of a laterally-movable ribbon-guiding frame, ribbon-spools movable with said frame, a reactive device for urging the frame in one direction, a shift-key for urging the frame in the opposite direction in opposition to said reactive device, and adjustable means for limiting the return movement of the shift-key.

12. In a type-writing machine, the combination with the frame and carriage, of a laterally-movable ribbon-guiding frame, ribbon-spools movable with said frame, spring-operated means for urging the frame constantly in one direction to present the ribbon at the printing-point, a shift-key for urging the frame laterally in the opposite direction to displace the ribbon from the printing-point, and an adjustable stop for limiting the return movement of the shift-key to present any desired impression track or stripe of the ribbon at the printing-point.

13. In a type-writing machine, the combination with the frame and carriage, of a laterally-movable ribbon-guiding frame supported by the carriage, ribbon-spools movable with said ribbon-guiding frame, a spring-urged rock-shaft connected to the ribbon-guiding frame, and a shift-key mounted upon the carriage for movement therewith and operatively connected to the shaft to rock the same.

14. In a type-writing machine, the combination with the frame and carriage, of a laterally-movable ribbon-guiding frame, a spring-urged rock-shaft connected to the opposite ends of said frame, a shift-key connected to the rock-shaft to operate the same, and an adjustable stop disposed in the path of the shift-key to limit the return movement thereof.

15. In a type-writing machine, the combination with the frame and carriage, of ribbon-supporting means, ribbon-shifting mechanism for moving the ribbon laterally, and a movable line-finder, said ribbon-shifting mechanism being operatively related to the line-finder.

16. In a type-writing machine, the combination with the frame and carriage, of ribbon-supporting mechanism, a shift-key for moving the ribbon laterally, and a line-finder shiftable toward and away from the printing-point and operatively related to the shift-key.

17. In a type-writing machine, the combination with the frame and carriage, of ribbon-supporting mechanism, a line-finder, and operating means common to the ribbon and line-finder for presenting them to the printing-point alternately.

18. In a type-writing machine, the combination with the frame and carriage, of ribbon-supporting means, a line-finder movable toward and from the printing-point, means for

shifting the ribbon laterally independently of the line-finder, to present any of the impression stripes or tracks of the ribbon to the printing-point, and means for automatically shifting the line-finder toward the printing-point whenever the ribbon is entirely displaced therefrom.

19. In a type-writing machine, the combination with the frame and carriage, of a laterally-movable ribbon-guiding frame, ribbon-spools movable therewith, a shift-key for moving the ribbon-frame laterally, a line-finder shiftable toward and from the printing-point, a rock-shaft supporting the line-finder, and connections between the shift-key and said rock-shaft.

20. In a type-writing machine, the combination with the frame and carriage, of a laterally-movable ribbon-guiding frame, ribbon-spools movable therewith, a line-finder movable toward and from the printing-point, a ribbon-shift key for moving the ribbon-guiding frame laterally, an arm operated by said key, and connections for operatively connecting said arm with the line-finder to operate the same during the final movement only of the shift-key in one direction.

21. In a type-writing machine, the combination with the frame and carriage, of a laterally-movable ribbon-guiding frame, ribbon-spools movable with said frame, a line-finder movable toward and from the printing-point, a rock-shaft connected to the line-finder to operate the same, a slide-bar operatively related to the rock-shaft, a shift-key for moving the ribbon-guiding frame, and an arm operated by said shift-key to urge the slide-bar in one direction.

22. In a type-writing machine, the combination with a spring-retracted laterally-movable ribbon-guiding frame, of a spring-retracted line-finder, and shifting means common to the ribbon-guiding frame and line-finder.

23. In a type-writing machine, the combination with the frame and carriage, of a ribbon-guiding frame formed with horizontal ribbon-guides along which the ribbon extends, said guides having portions thereof depressed below the plane of the frame to present the ribbon in closely-adjacent relation to the platen at the printing-point.

24. In a type-writing machine, the combination with the frame and carriage, of a ribbon-guiding frame, ribbon-spools located at the opposite ends of the ribbon-guiding frame, and ribbon-guards detachably secured to said frame.

25. In a type-writing machine, the combination with the frame and the carriage, of ribbon-spools supported by and movable with the carriage, a ribbon-guiding frame extending from one to the other of said spools, and ribbon-guards detachably secured to said ribbon-guiding frame.

26. In a type-writing machine, the combination with the frame and the carriage pro-

vided with a pendent type-ring, of ribbon-spools mounted at the opposite ends of the carriage, a ribbon-guiding frame connected at its opposite ends to said spools and extended under the pendent type-ring, and a detachable ribbon-guard secured to the ribbon-guiding frame and extended under the horizontal portion thereof to prevent the contact of the ribbon with the work-sheet except at the printing-point.

27. The combination with the ribbon-guiding frame of a type-writing machine, of a ribbon-guard provided with flanges engaging the opposite edges of said frame.

15 28. The combination with the ribbon-guiding frame of a type-writing machine, of detachable ribbon-guards provided with flanges, and gripping-arms engaging the opposite edges of the frame.

20 29. In a type-writing machine, the combination with a frame and carriage, of ribbon-supporting mechanism designed to support a ribbon having longitudinal impression tracks or stripes of different colors, and a ribbon-indicator having colored characters corresponding in number and color to the impression-stripes on the ribbon.

30 30. In a type-writing machine, the combination with a frame and carriage, a ribbon having impression stripes or tracks of different colors, ribbon-supporting mechanism, and means for shifting the ribbon laterally, of a ribbon-indicator mounted on the carriage and disposed in significant relation to the ribbon-shifting means to indicate the impression stripe or track presented at the printing-point, said ribbon-indicator being provided with characters corresponding in color and number to the impression-stripes of the ribbon.

40 31. In a type-writing machine, the combination with the frame and carriage, of ribbon-supporting means, a line-finder movable toward and from the printing-point, means for shifting the ribbon laterally independent of the line-finder, and means for automatically shifting the line-finder toward the printing-point whenever the ribbon is entirely displaced therefrom.

45 32. In a type-writing machine, the combination with the frame and carriage, of ribbon-supporting means, means for shifting the ribbon-supporting means laterally, and adjustable means for arresting said ribbon-supporting means upon its return, the adjustment of the arresting means being unaffected by the shifting of the ribbon.

50 33. In a type-writing machine, the combination with the frame and carriage, of ribbon-supporting means, means for shifting the ribbon laterally, and adjustable means for arresting the ribbon upon its return, the adjustment of the arresting means being unaffected by the shifting of the ribbon.

65 34. In a type-writing machine, the combination with the frame and carriage, of ribbon-supporting means, means for shifting the ribbon-supporting means laterally, and an adjustable stop for arresting the return movement of the ribbon-supporting means, said ribbon-supporting means permitting the shifting of the ribbon without interfering with the adjustment of the stop.

70 35. In a type-writing machine, the combination with a frame and carriage, of ribbon-supporting means, means for shifting the ribbon laterally, means for returning the ribbon, and adjustable means for arresting the ribbon in different positions with respect to the printing-point, said shifting means permitting the ribbon to be shifted without interfering with the adjustment of the arresting means.

75 36. In a type-writing machine, the combination with a frame and carriage, of ribbon-supporting means, means for shifting the ribbon away from the printing-point, reactive means for returning the ribbon, and an adjustable stop device for limiting said return movement, said shifting means permitting 80 the shifting of the ribbon without interfering with the adjustment of the stop device.

85 37. In a type-writing machine, the combination with a frame and carriage, of ribbon-supporting means, a ribbon-shift key located 95 at or adjacent to the keyboard and arranged to shift the ribbon laterally, reactive means for returning the ribbon, and an adjustable stop disposed to limit the return movement of the ribbon-supporting means, the key and 100 stop being so related that the adjustment of the stop will not be disturbed by the movement of the key.

90 38. In a type-writing machine, the combination with the frame and carriage, of a ribbon-supporting frame mounted on the carriage, a lever pivotally mounted intermediate 105 of its ends upon the carriage, said lever having connection at one end with the ribbon-supporting frame and provided at its opposite end with a shift-key, and an adjustable stop device mounted on the carriage and disposed in the path of said lever.

100 39. In a type-writing machine, the combination with the frame and carriage, of ribbon-supporting mechanism, means for moving the ribbon-supporting mechanism laterally, and a line-finder separate from the ribbon-supporting mechanism and operatively related to the ribbon-moving means to be shifted 110 thereby toward and away from the printing-point.

115 40. In a type-writing machine, the combination with the frame and carriage, of ribbon-supporting mechanism, a line-finder separate 125 from the ribbon-supporting mechanism, and operating means common to the ribbon-supporting mechanism and line-finder for presenting them to the printing-point alternately.

120 41. In a type-writing machine, the combination with the frame and carriage, of ribbon-supporting mechanism, a shift-key for moving the ribbon-supporting mechanism laterally, and a line-finder mounted independ- 130

ently of the ribbon-supporting mechanism and shiftable toward and away from the printing-point, said line-finder being operatively related to the shift-key.

42. In a type-writing machine, the combination with the frame and carriage, of ribbon-supporting means, a device for shifting the ribbon-supporting means laterally, means for returning the ribbon-supporting means, and
10 an adjustable stop for arresting the ribbon-supporting means in various positions upon its return, the shifting device and the adjustable stop being so related that the adjustment of the stop will not be interfered with
15 by the movement of the device.

43. In a type-writing machine, the combination with the frame and carriage, of ribbon-supporting means, a ribbon-shift key located at or adjacent to the keyboard and arranged
20 to shift the ribbon laterally, and an adjustable stop disposed to limit the return movement of the ribbon-supporting means, the shift-key and stop being so related that the adjustment of the stop will not be disturbed
25 by the movement of the key.

44. In a type-writing machine of the downwardly-striking type, the combination with a frame and carriage, of ribbon-spool shafts supported at the opposite ends of the carriage, a type-bar support pendent from the carriage, a ribbon supporting and guiding frame pendent from the shafts and extended under the type-bar support, and ribbon-spools mounted on the shafts and engaging the opposite ends of the ribbon supporting and guiding frame, whereby the spools and frame may be shifted laterally in unison, said frame having an opening at the printing-point and means for depressing that portion of the ribbon located opposite the opening.

45. In a type-writing machine, the combination with a frame and carriage, of spool-shafts, spools mounted on the shafts, and a ribbon supporting and guiding frame having
45 its opposite ends carried by the shafts, said last-named frame having an opening at the printing-point, and a plurality of parallel guiding-fingers located adjacent to each side of the opening and extending in the same direction to permit the threading of the ribbon over and under said fingers by the edgewise movement of said ribbon, substantially as and for the purpose described.

46. In a type-writing machine, the combination with a frame and carriage, of ribbon-spool shafts, ribbon-spools, and a ribbon sup-

porting and guiding frame extending between the shafts, said last-named frame comprising angular end portions supported from the shafts, and an intermediate ribbon-plate having an opening and a plurality of forwardly-extending ribbon-guiding fingers at each side of the opening, between which fingers the ribbon may be slipped edgewise from the front of the frame.

47. In a type-writing machine, the combination with a frame and carriage, of ribbon-spool shafts, ribbon-spools, and a ribbon supporting and guiding frame extending between the shafts, said last-named frame comprising angular end portions supported from the shafts, and an intermediate ribbon-plate having a plurality of forwardly-extending ribbon-guiding fingers, between which the ribbon may be slipped laterally from the front of the frame, the guiding-fingers immediately adjacent to the printing-point being formed with ribbon-depressing flanges.

48. In a type-writing machine, the combination with a frame and carriage, of spool-shafts and spools, a type-bar-supporting ring provided with guide-loops, a ribbon supporting and guiding frame extending between the spools and under the type-bar-supporting ring, and studs extending from said frame and engaging the guide-loops.

49. In a type-writing machine, the combination with a frame and carriage, of ribbon-supporting means, a line-finder movable toward and from the printing-point, means for shifting the ribbon laterally independently of the line-finder, and means for shifting the line-finder toward the printing-point when the ribbon is displaced therefrom.

50. In a type-writing machine, the combination with a frame and carriage, of ribbon-supporting means, a line-finder movable toward and from the printing-point, means for shifting the ribbon laterally independently of the line-finder, and means for automatically shifting the line-finder toward the printing-point after predetermined independent movement of the ribbon.

In testimony that we claim the foregoing as our own we have hereto affixed our signatures in the presence of two witnesses.

CHARLES FREDERICK LAGANKE.
JOHN A. SMITH.
